US0D1034521S

(12) **United States Design Patent** (10) Patent No.: **US D1,034,521 S**
(45) Date of Patent: ** Jul. 9, 2024

(54) EARPHONES	D246,242 S	11/1977	Bellini
(71) Applicant: GN Audio A/S , Ballerup (DK)	D254,183 S	2/1980	Doodson
(72) Inventor: Bill Zeng , Ballerup (DK)	D262,019 S	11/1981	Upshaw
(73) Assignee: GN AUDIO A/S , Ballerup (DK)	D299,337 S	1/1989	Wiegel
(**) Term: 15 Years	D327,888 S	7/1992	Fitzgerald
(21) Appl. No.: 29/910,477	D328,461 S	8/1992	Daido et al.
(22) Filed: Aug. 21, 2023	D337,118 S	7/1993	Seikita
	D340,932 S	11/1993	Yan
	D358,391 S	5/1995	Isono
	D376,598 S	12/1996	Hayashi
	D391,573 S	3/1998	Nakamura
	5,809,573 A	9/1998	Bary
	6,081,604 A *	6/2000	Hikichi .....
			H04R 5/0335
			381/124
	D431,550 S	10/2000	Yoneda

(57) **CLAIM**

The ornamental design for an earphones, as shown and described.

DESCRIPTION

FIG. 1 is a top front perspective view of earphones showing the new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The features shown in broken lines depict environmental subject matter only and form no part of the claimed design.

1 Claim, 6 Drawing Sheets
